UNITED STATES PATENT OFFICE.

WILLIAM S. LOUGEE, OF ROCHESTER, NEW HAMPSHIRE, ASSIGNOR TO J. SPAULDING AND SONS COMPANY, OF ROCHESTER, NEW HAMPSHIRE, A FIRM COMPOSED OF LEON C. SPAULDING, HUNTLEY N. SPAULDING, AND ROLAND H. SPAULDING, ALL OF ROCHESTER, NEW HAMPSHIRE, AND EMMA C. SPAULDING AND MARION L. SPAULDING, BOTH OF BOSTON, MASSACHUSETTS.

SHOE-FORM.

1,128,160.

Specification of Letters Patent. Patented Feb. 9, 1915.

Application filed November 12, 1912. Serial No. 730,863.

To all whom it may concern:

Be it known that I, WILLIAM S. LOUGEE, a citizen of the United States, residing at Rochester, in the county of Strafford and 5 State of New Hampshire, have invented certain new and useful Improvements in Shoe-Forms; and I do hereby declare the following to be a full, clear, and exact description of the invention, such as will enable others 10 skilled in the art to which it appertains to make and use the same.

The present invention relates to shoe forms and more particularly to hollow shoe forms made of fiber or like material.

15 The object of the present invention is to produce a hollow shoe form of fiber or like material which is provided with a wire brace extending across the ball portion to stiffen the shoe form and fix its width, 20 which, because of its construction, is rigidly held in place on the shoe form.

The present invention contemplates the production of a shoe form which can be easily and cheaply manufactured.

25 With the above object in view, the present invention consists in the shoe form herein-after described and particularly pointed out in the claim.

In the drawings which illustrate the preferred embodiment of the present invention, Figure 1 is a side elevation of the shoe form; and Fig. 2 is a bottom view.

Referring to the drawings, the shoe form comprises a hollow, shell-like body of fiber 30 such as leatherboard, fiberboard and the like. The body comprises a fore-part 1 and a heel part 2 which are hinged to each other by means of rivets 3 so that the heel-part can be turned up when the form is put in 40 the shoe and then pressed down into the position shown in Fig. 1 to press the fore-part 1 forwardly into the shoe. The forepart is provided with a wire brace 4 which extends across the ball portion of the fore-part.

45 The wire brace has its ends bent over at substantially right angles to the brace to form feet 5 which extend in opposite directions. The wire brace at the ends of the feet is looped to form eyes 6 through which are 50 passed the pronged ends of rivets 7 which secure the brace to the body portion. The rivets 7 have smooth heads at the outer side

of the shoe form. The shoe form has an opening 8 in the bottom which extends from toe to heel of the form. The fore-part is 55 presented to a riveting machine and one end of the brace 4 is secured to the side of the fore-part by means of one of the rivets 7. Then, the form is placed in a hollow mold or jig which has the same width as the 60 width to be given to the form. The free end of the brace 4 is brought toward the opposite side of the fore-part and is slid along the inside of the fore-part until it presses the opposite sides of the ball portion 65 against the inside of the mold. The brace 4 is now in a position in which it fixes and braces the fore-part to the exact width which is desired. Then, while the brace is held in this position, the fore-part is presented to a riveting machine which secures the free end of the brace 4 in place by means of the other rivet 7. The brace 4 extends across the fore-part where there exists the greatest need of stiffening and keeps the 75 semi-flexible fiberboard from contracting the width of the opening 8 in its bottom. The feet 5 of the brace 4 extend in opposite directions so that the brace is rigidly secured in place by the rivets 7 and can not be 80 twisted after it is secured. It will be seen that neither one of the feet 5 can turn about its rivet because the other foot extends from the brace in the opposite direction and acts as a lever arm to keep the first foot from 85 twisting. Thus, if the middle of the brace 4 is pressed upwardly, one foot will tend to turn in one direction about its rivet and the other foot in the opposite direction, so that they will counteract each other and the 90 brace 4 will be rigidly held from turning.

While the preferred embodiment of the present invention has been specifically illustrated and described, it is to be understood, however, that the present invention is not 95 limited to the construction which forms the preferred embodiment, but may be embodied in other structures within the scope of the invention as defined in the following claim.

I claim—

A shoe form having, in combination, a hollow, shell-like body of fiber or like material having a longitudinal opening in the bottom, a stiff wire brace extending laterally

across the opening at the ball portion of the form and having feet which extend at substantially right angles to the brace in opposite directions with rivet-receiving eyes at 5 their ends, and rivets passing through the eyes and through the sides of the body for securing the ends of the wire brace to the

body at opposite sides of its ball portion, substantially as described.

WM. S. LOUGEE.
